UNITED STATES PATENT OFFICE.

EDWARD F. DEACON, OF ST. LOUIS, MISSOURI, ASSIGNOR TO GUS V. BRECHT BUTCHERS' SUPPLY COMPANY, OF ST. LOUIS, MISSOURI, A CORPORATION OF MISSOURI.

REFRIGERATOR DISPLAY CASE.

Application filed February 6, 1926. Serial No. 88,378.

My invention relates to a refrigerated case for the display of meats, meat products and other food products requiring low temperatures for preservation. One object of my invention is to provide a case which will not only be efficient from the standpoint of amount of refrigerant required, but one in which the products refrigerated are swept by a continuously moving current of cold air. This is advantageous particularly in connection with meat products which continuously evolve gases and develop heat, and results in these products being more quickly and evenly cooled and maintained in a cool condition than if they are merely kept immersed in cold air which is stationary except for convection currents set up only by the development of heat at particular points on the surfaces of the meat.

My display case is intended for use with a local mechanical source of refrigeration located adjacent to it and which automatically starts and stops in accordance with the temperature within the case.

A further object of my invention is to provide a "hold over" tank of brine whereby the interval between stopping and starting of the refrigerating machine may be increased, and to so arrange this tank as not to thereby decrease the available display space in the case.

Other objects and advantages of my invention will appear from the following more detailed description.

The accompanying drawing is a cross sectional view of a display case embodying my invention.

The display compartment of the case is formed by bottom, top, end and front and rear walls, as shown, the front wall being formed of spaced plates of glass 1, and the rear wall being provided with sliding doors 2 permitting access to the interior. The bottom of the case is provided with supports 3 on which meat display platters 4 may be placed and by means of which they are spaced above the bottom of the case. The brine tank 5 is located along the rear wall of the case and its upper surface also provides a support for meat platters. Expansion coils 6 are located in the top of the case directly above the main meat display platters and are in circuit with expansion coils 7 located in the brine tank. These expansion coils are connected to the refrigerant com-

pressor (not shown) the refrigerant being first discharged into the coils in the upper part of the case. The expansion coils are concealed from view, coils 6 by the opaque top wall of the case, and coils 7 by the brine tank.

Beneath the coils in the upper part of the case I position a deflector plate whose upper surface slopes downward toward the rear of the case, and whose under surface slopes upward toward the front of the case. This plate is so dimensioned as to extend across the whole area directly beneath the coils but to provide air passages between its edges and the rear and front walls of the case. The edge of the deflector adjacent the rear wall of the case is turned up and the deflector slopes slightly longitudinally of the case whereby a trough is formed which carries away water dripping from the surfaces of the expansion coils. Preferably the upper and lower surfaces of the deflector plate are separated by heat insulating material such as cork.

In the operation of the case described, the refrigerant in its coldest condition as it leaves the expansion valve is delivered into the expansion coils at the top of the case where the air is warmest. The rapid exchange resulting from this condition quickly cools the air which falls downward to the deflector plate and by which it is directed rearwardly, as shown by the arrows. This motion of the air creates a suction drawing warmer air from the upper part of the front of the case through the passage between the deflector and the front wall and into contact with the expansion coils. Some of the falling air also comes into contact with the surface of the brine tank where it is further cooled and, due to the action of the coils and deflector in the top of the case, a circulating current of air is set up over and beneath the meat display container which moves constantly in the path indicated by the arrows. Thus the meat is quickly cooled and more evenly maintained in a cool condition than if the continuous and relatively rapid circulation of air produced by the arrangement described did not exist and the air moved in irregular paths and had a relatively slow rate which would result from the prior practice, as known to me, of merely locating cooling coils in a case at the rear wall thereof, or at some other convenient point and

without providing means for continuously causing a current of cooled air to move over the surface of the meat. So directing the air currents that the air while passing adjacent to the glass wall of the case is at its highest temperature prevents "frosting" of the glass which would impair visibility.

The operation described is continuous even when the refrigerating machine is not in operation and so long as the temperature of the coils in the top of the case is lower than that of the air which comes into contact therewith.

The expression "refrigerating coils" used in the claims is intended to include a single pipe or container of refrigerating fluid as well as the usual plurality of pipes commonly referred to as "coils."

Having fully described my invention, what I claim as new and desire to secure by Letters Patent of the United States is:

1. In a refrigerated display case, the combination of means forming a refrigerating chamber having a transparent front wall, means for supporting in the lower part of the chamber the products to be refrigerated, refrigerating coils located in the upper part of the chamber, and a deflector plate beneath the coils and sloping laterally toward the rear of the chamber, said plate being dimensioned to provide air passages between it and the rear and front walls of the chamber.

2. In a refrigerated display case, the combination of means forming a refrigerating chamber having a transparent front wall, means for supporting in the lower part of the chamber the products to be refrigerated, refrigerating coils located in the upper part of the chamber and other refrigerating coils located in the lower rear part of the chamber and not directly beneath the first named coils, and means directing toward the rear of the chamber air cooled by the upper coils.

3. In a refrigerated display case, the combination of means forming a refrigerating chamber, means for supporting in the lower part of the chamber the products to be refrigerated, refrigerating coils located in the upper part of the chamber and other refrigerating coils in circuit therewith and located in the lower part of the chamber and not directly beneath the first named coils, means directing toward the wall of the chamber nearest the second mentioned coils air cooled by the upper coils, and a source of refrigerant supply so connected that the refrigerant is first discharged into the coils at the top of the chamber.

4. In a refrigerated display case, the combination of means forming a refrigerating chamber having a transparent front wall and an opaque top, means for supporting in the lower part of the chamber the products to be refrigerated, refrigerating coils located immediately beneath the top of the

case, and a horizontally extending deflector plate in the upper portion of the case and beneath the coils, the upper surface of said plate sloping downward in lateral direction toward the rear of the case and its lower surface sloping upward in lateral direction toward the front wall of the case, the space above the deflector plate being in communication with the space beneath along both the front and rear of the case whereby air currents are produced passing from the refrigerating coils downward along the rear wall of the case, over the products to be refrigerated and upwardly adjacent to the front wall of the case to the refrigerating coils.

5. In a refrigerated display case, the combination of means forming a refrigerating chamber having a transparent front wall and an opaque top, means for supporting in the lower part of the chamber the products to be refrigerated, refrigerating coils located immediately beneath the top of the case, a horizontally extending deflector plate in the upper portion of the case and beneath the coils, the upper surface of said plate sloping downward in lateral direction toward the rear of the case and its lower surface sloping upward in lateral direction toward the front wall of the case, the space above the deflector plate being in communication with the space beneath along both the front and rear of the case whereby air currents are produced passing from the refrigerating coils downward along the rear wall of the case, over the products to be refrigerated and upwardly adjacent to the front wall of the case to the refrigerating coils, and a refrigerated brine tank located in the bottom of the chamber along the rear wall thereof and in the path of air currents passing downwardly from the refrigerating coils in the top of the case.

6. In a refrigerated display case, the combination of means forming a refrigerating chamber having a transparent front wall and an opaque top, means for supporting in the lower part of the chamber the products to be refrigerated, refrigerating coils located immediately beneath the top of the case, a horizontally extending deflector plate in the upper portion of the case and beneath the coils, the upper surface of said plate sloping downward in lateral direction toward the rear of the case and its lower surface sloping upward in lateral direction toward the front wall of the case, the space above the deflector plate being in communication with the space beneath along both the front and rear of the case whereby air currents are produced passing from the refrigerating coils downward along the rear wall of the case, over the products to be refrigerated and upwardly adjacent to the front wall of the case to the refrigerating coils, a refrigerated brine tank located in the

- bottom of the chamber along the rear wall thereof and in the path of air currents passing downwardly from the refrigerating coils in the top of the case, additional refrigerating coils in said tank and in circuit with the coils in the top of the case, and a source of refrigerant supply so connected that the refrigerant is first discharged into said top coils.
7. In a refrigerated display case, the combination of means forming a refrigerating chamber having a transparent front wall, means for supporting in the lower part of the chamber the products to be refrigerated, refrigeration means for the chamber located in the upper part thereof, and air circulation controlling means beneath the refrigeration means adapted to cause substantially all of the air cooled by said means to be discharged along the rear of the chamber, the space within which said refrigeration means is located being also in communication with the lower part of the chamber along the front of the chamber, whereby a path of air circulation is established which embraces the products to be refrigerated and causes air warmed thereby to pass adjacent to the transparent front wall of the chamber.
8. In a refrigerated display case, the combination of means forming a refrigerating chamber having a transparent front wall and a rear wall provided with an opening with removable closure to permit access to the chamber, means for supporting in the forward lower part of the chamber the products to be refrigerated, refrigerating coils located in the upper part of the chamber above the level of the access opening, means adapted to discharge toward the rear of the chamber the air cooled by said coils, and a brine tank extending along the rear of the lower part of the chamber and beneath the level of the access opening but extending above the level of the aforesaid means for supporting the products to be refrigerated.

In testimony whereof, I hereunto affix my signature, this 2nd day of February, 1926.

EDWARD F. DEACON.
